UNITED STATES PATENT OFFICE.

WILLIAM LAWRENCE, OF CHICAGO, ILLINOIS.

AUXILIARY STARTER-CONTROL DEVICE.

1,397,690.

Specification of Letters Patent.

Patented Nov. 22, 1921.

Application filed February 28, 1921. Serial No. 448,506.

To all whom it may concern:

Be it known that I, WILLIAM LAWRENCE, a citizen of the United States, and a resident of the city of Chicago, in the county of Cook

5 and State of Illinois, have invented certain new and useful Improvements in an Auxiliary Starter-Control Device; and I do hereby declare that the following is a full, clear, and exact description of the same, reference being had to the accompanying drawings, and to the numerals of reference marked thereon, which form a part of this specification.

This invention relates to an auxiliary 15 starter control device and particularly to a device which is adapted to be used in connection with starting motors such as are used on motor vehicles at the present time. These starting motors are used to start internal 20 combustion engines which propel motor vehicles and are ordinarily driven by electric current which is supplied by a storage battery mounted on the vehicle. It is a well-known fact that large quantities of electrical 25 energy are required to start the electric motor to effect an initial rotation of the engine. The amount of current required of course decreases as soon as the rotation of the engine is begun and it is apparent that much of the 30 electrical energy consumed could be saved if the initial rotation of the engine were manually aided. This has been accomplished heretofore by one person operating the starting crank at the front of the vehicle 35 while another depresses the starter switch pedal from the driver's position. The effecting of this method, however, requires two persons and is consequently impractical when only the driver of the vehicle is present. It is therefore desirable that an arrangement be provided which will enable the operator of a motor vehicle to simultaneously 40 actuate an automatic starter control and a manual starting device.

45 It is an object of this invention to provide auxiliary controlling means for an internal combustion engine starting system, which may be operated simultaneously with the operation of the engine starting crank, by a single operator.

50 It is another object of this invention to provide means whereby a starter control switch mounted at one end of an internal combustion engine may be operated from the other end of the engine.

55 It is a further object of this invention to

provide a pivotally mounted device for actuating a starter control, and means for operating said pivotally mounted device from a distance.

60 It is also an object of this invention to provide an auxiliary starter control actuating device which is adjustable for use with starter control pedals of different heights.

65 It is an important object of this invention to provide means whereby automatic and manual motor starting devices may be simultaneously operated by one person.

70 Other and further important objects of this invention will be apparent from the disclosures in the specification and the accompanying drawings.

75 The invention in a preferred form is illustrated in the drawings and hereinafter more fully described.

On the drawings:

Figure 1 is a fragmentary top plan view of a motor vehicle chassis showing the auxiliary starter control device of this invention installed thereon.

80 Fig. 2 is an enlarged fragmentary section on the line 2—2 of Fig. 1, showing the auxiliary starter control device in position for use.

85 Fig. 3 is a fragmentary sectional view similar to Fig. 2 showing a modified form of the device.

Fig. 4 is a top plan view of the device shown in Fig. 2.

Fig. 5 is a top plan view of the device shown in Fig. 3.

As shown on the drawings:

The reference numeral 1 indicates the front portion of a motor vehicle chassis in which an internal combustion engine 2 is mounted. In order to start said internal combustion engine it is necessary that the crank shaft thereof be initially rotated from an outside source, and for effecting this rotation an electrically actuated starting motor 3 is ordinarily provided. This rotation may also be effected by a starting crank 4 which is ordinarily connected to the front end of the engine crank shaft by a suitable clutch connection and which extends outwardly in front of a radiator 5 which is normally mounted on the front end of the chassis 1.

The electric starting motor 3 is put in operation by connecting the same with a suitable source of electrical energy such as a storage battery and this connection is ordinarily effected through a switch (not shown)

which is actuated by a pedal 6 extending through a floor board 7 mounted on the chassis 1 in rear of a dash board 8 and the engine 2. Said pedal 6 is ordinarily depressed by the foot of the operator of the vehicle when it is desired to start the engine 2, and this invention provides means whereby said pedal may be depressed by the operator when standing in front of the radiator 5 in order that the crank 4 may be utilized to aid the electric motor 3 in turning over the engine.

The device comprises a block 9 which is secured to the floor board 7 by screws 10 or other suitable means and connected to said block 9 by a hinge connection 11 is a plate 12, which is provided with a downwardly extending apertured internal flange 13, and which engages the head 14 of the pedal 6. Connected in the aperture in the flange 13 is a flexible cord or wire 15 which extends downwardly through an aperture 16 in the floor board 7 and forwardly along the side of the engine 2 inside the chassis 1, whence it extends through an aperture in the frame of the radiator 5 and outwardly to a position adjacent the crank 4, as clearly shown in Fig. 1. In order that said outwardly extending end of the wire 15 may be conveniently grasped by the operator, a loop 17 is ordinarily formed therein.

On account of the varying heights of the pedals 6 above the floor board 7 in different makes of vehicles, it is often desirable to provide an arrangement whereby the plate 12 and the hinge connection therefor may be elevated from or depressed toward said floor board as may be required. The arrangement provided by this invention for accomplishing the adjustment of the height of said plate 12 and the hinge connection is clearly shown in Figs. 3 and 5, and, as shown in said figures, the plate 9 is replaced by a plate 18 which is secured to the floor board by means of screws 19 and which is provided with a pair of integral upwardly extending lugs 20, at one end thereof. Said lugs 20 are provided with oppositely positioned central apertures and pivoted on a shaft or bolt 21 extending through said apertures is a channel link 22 which is provided at its outer end with oppositely positioned apertures through which a shaft 23 affording a pivotal or hinge connection for the plate 12 extends. Said shafts or bolts 21 and 23 are respectively secured in position by means of heads 24 and 25 and cotter pins 26 and 27.

As shown in Fig. 3, the lugs 20 are provided with a plurality of oppositely positioned apertures 28 and a pin 29 engaged through a pair of said apertures and through oppositely positioned apertures in the upstanding portions of the link 22 is adapted to secure said link in position at the desired adjusted height.

The operation of the device of this invention will be evident from the foregoing description. When it is desired to start the engine 2 the operator may grasp the loop 17 on the wire 15 and pull said wire outwardly, thus moving the plate 12 about its pivotal or hinged connection and depressing the pedal 6, whereby the starting motor 3 is connected with a source of electrical energy. The operator may at the same time grasp the starting crank 4 with the other hand and rotate the same to aid the electric motor in starting rotation of the crank shaft of the engine. By thus aiding the electric motor with the crank a great saving in electrical energy is effected and it is possible to start the engine easily even in cases where the storage battery is nearly exhausted.

It is thus apparent that this invention provides a convenient arrangement whereby automatic and manual means for the starting of an internal combustion engine may be simultaneously operated so that the engine may be started with a minimum of strain on the automatic means and with a slight effort in the operation of manual means. It is of course obvious that the device of this invention may as well be used in connection with starting devices which are propelled by compressed air or other motive power, the plate 12 in these cases being used to depress suitable valve pedals. When not in use the plate 12 may be folded back out of the way or may be left on the pedal where it may be engaged by the foot of the operator in the usual manner, whereupon the full pressure of the operator's foot is applied to the pedal.

I am aware that numerous details of construction may be varied through a wide range without departing from the principles of this invention, and I therefore do not purpose limiting the patent granted otherwise than necessitated by the prior art.

I claim as my invention:

1. In a motor vehicle the combination with an internal combustion engine, of manually operated means for rotating said engine mounted at one end thereof, power operated means for rotating the engine, means for controlling said power operated means from the end of the engine opposite the manually operated means, and an auxiliary mechanism for actuating said controlling means from the same end of the engine as the manually operated means.

2. In a motor vehicle the combination with an internal combustion engine, of manually operated means for rotating said engine mounted at one end thereof, power operated means for rotating the engine, means for controlling the power operated means from the end of the engine opposite the manually operated means, and a pivotally mounted auxiliary mechanism for actu-

ating said controlling means from the same end of the engine as the manually operated means.

3. In a motor vehicle the combination

5 with an internal combustion engine, of manually operated means for rotating said engine mounted at one end thereof, power operated means for rotating the engine, means for controlling said power operated
10 means from the end of the engine opposite the manually operated means, auxiliary mechanism for actuating said controlling means from the same end of the engine as the manually operated means, and means for
15 adjusting the auxiliary mechanism for various controlling means.

4. In a motor vehicle having separate manual and automatic motor starting means, means for controlling the automatic start-

20 ing means located in a position which is inaccessible from the manual starting means, and an auxiliary mechanism for operating said controlling means from a position which is accessible from the manual starting
25 means.

5. In a motor vehicle the combination with

a starter control pedal, of pivotally mounted means for depressing the same, and a connection from said pivotally mounted means to the front of the motor vehicle.

30

6. A starter pedal control device comprising fixed means, a plate hinged on said fixed means and adapted to contact the top of the starter pedal, and a flexible connection secured to the outer end of said plate and 35 adapted to be operated to pull said plate downwardly and depress the pedal.

7. A starter pedal control device comprising fixed means, a link pivotally mounted thereon, a plate pivotally mounted in the 40 outer end of the link and engaging the top of the starter pedal, a flexible connection in the outer end of said plate, and means for securing the link in a plurality of angular positions relative to said fixed means.

45

In testimony whereof I have hereunto subscribed my name in the presence of two subscribing witnesses.

WILLIAM LAWRENCE.
